FOMENTATION HEATER AND WRINGER

Walter Morten, Olive D. Richter, and Susan
Torpey, Alameda, Calif.

Application June 13, 1933, Serial No. 675,548

4 Claims. (CL 128—268)

This invention relates to improvements in fomentation heaters and wringers.

Among the objects of the invention is to provide means for preparing hot fomentations without scalding the hands of the operator.

Another object is to provide a portable apparatus for this purpose.

Another object is to combine simplicity and strength in a portable apparatus, electrically heated, sanitary and adaptable for operation at the bedside of the patient.

Other objects and advantages will appear as the description progresses.

The therapeutic value of hot fomentations is well recognized in the healing art, but their preparation involves many tedious operations. Heretofore, it has been impracticable to prepare them at the bedside or place of application for the lack of proper apparatus. The present invention eliminates these and many other incidental objections. Broadly stated, the invention consists of combined means for boiling water in a container, submerging the fomentation pad therein, then elevating and then squeezing the surplus water from the pad before removing it from the container.

In this specification and the accompanying drawings, the invention is disclosed in its preferred form. It is to be understood however that it is not limited to this form, because it may be embodied in other forms without departing from the spirit of the invention as defined in the claims following the description.

In the two sheets of drawings:

Fig. 1 is a vertical section of a water heating container having a squeezing mechanism combined therewith in accordance with this invention.

Fig. 2 is a similar view showing the squeezing mechanism tilted for the delivery of the pad.

Fig. 3 is an enlarged fragmentary detail in side elevation partly in vertical section of the rack and pinion gearing of the squeezer.

Fig. 4 is a similar view of the spring stop mechanism of the depresser.

In detail, the construction illustrated in the drawings, referring particularly to Fig. 1, comprises a tank or vessel 1, preferably composed of tinned copper or other suitable noncorrosive material. The tank rests upon suitable legs such as 2 in the table sizes. The larger sizes can be mounted upon longer legs with rollers to rest upon the floor.

The electric immersion heating element 3 extends through and is sealed in the wall of the

tank and extends across the length thereof near the bottom. It should be of sufficient capacity to heat the water in the tank to the boiling point quickly.

The tank has the substantial cover 4 with the internal flange 5 fitting snugly within the reinforced upper edge of the tank. The cover is hinged at 6 to the upper edge of the tank and has the latch 7 at the opposite side of the tank. This cover is preferably cast of a suitable non-corrosive alloy to simplify the assembly and give the necessary strength to withstand the squeezing action. This cover should fit tightly enough to retain the vapor but not to cause a pressure to build up in the tank 1.

The squeezer comprises the base 8 fixed to the top of the cover with the standard 9 having the aligned guides 10 and 11 thereon. The head of the standard has a transverse hole to receive the pinion 12, the teeth of which extend into the guide 10. The hub of the pinion extends outward from the head to receive the lever 13 fixed therein and provided with the convenient handle 14.

The rod 15 is slidable in the guides 10 and 11 and has the rack teeth 16 enmeshed with the teeth of the pinion 12, see Fig. 3. The rod extends downward into the tank 1 and has the squeeze plate 17 fixed thereon. This plate is reinforced with ribs to prevent bending when pressure is applied by the rod. This plate may be perforated to facilitate the drainage of water therethrough while functioning.

The depresser plate 18 has the stem 19 guided in the cover at 20. It has the annular grooves 19' and 19'' to engage a frictional latch 21 embedded in the socket 22, see Fig. 4. The cover is countersunk to pass the hub 23 of the plate 18 so that it can seat flat against the inside of the cover. This plate also may be perforated to permit the escape of water from the compress pad 24.

This pad may be of any conventional material in accordance with common practice such as crash toweling folded back and forth upon itself to fit the size of the squeeze plate 17. The folded pad is laid upon a perforated screen tray 25 having the wire handle 26 around which the edges of the tray are curled to reinforce and stiffen the tray.

The gage glass 27 is provided to indicate the water level within the tank. The thermometer 28 may be submerged within this gage tube to indicate the temperature of the water.

This invention operates substantially as fol-

lows: The tank 1 is filled with water up to about the level x as indicated on the gage 27. The heater 3 is then energized and the body of water heated to the desired temperature as indicated by the thermometer 28.

5 The pad 24 is folded and laid upon the tray 25. The latch 7 is then released and the cover lifted upon the hinge 6 as in Fig. 2 and the tray placed upon the plate 17 and hand pressure applied to the stem 19 to lower the depresser plate 18 upon the pad until the latch 21 engages the groove 19' to prevent the pad floating upward when the pad is submerged.

10 The cover 4 is then lowered to rest upon the top of the tank, as in Fig. 1. This submerges the pad and raises the water level to x' until the pad is properly heated. The handle 14 is then rotated clockwise which rotates the pinion 12 to lift the rack and rod 15 and the squeeze plate 17. This elevates the pad 24 overcoming the spring latch 21 until the depresser 18 rests against the cover 4 and the pad is elevated above the water level. Further downward pressure upon the handle 14 will squeeze the excess water from 15 the pad to the extent desired. The flange 5 prevents the escape from the tank of any water jetted outward by the squeezing operation.

20 When the handle 14 is raised and the cover swung upward, as in Fig. 2, the tray handle 26 is 30 grasped and the tray 25 and pad 24 withdrawn from the tank and the cover lowered to retain the heat and incidental vapors within the tank while the hot compress is being applied in accordance with the technique indicated.

25 The spring latch 21 engages the groove 19" when the compress is squeezed as in Fig. 2 to retain the plate 18 in raised position to permit easy withdrawal of the tray 25 and the compress thereon.

30 Having thus described this invention, what is claimed and desired to secure by Letters Patent is:

1. A fomentation pad heater and wringer including a tank adapted to contain liquid and having a cover hinged thereto and closing said tank; means for heating said liquid; a squeeze plate within said tank and having a rod extending through said cover; means for raising and lowering said rod; and a depresser interposed between said plate and cover and having a stem extending through said cover.

5

2. A fomentation pad heater and wringer including a tank adapted to contain liquid and having a cover hinged thereto and closing said tank; means for heating said liquid; a squeeze plate within said tank; external means for raising and lowering said plate with respect to said 15 cover; a depresser interposed between said plate and cover and having a stem extending through said cover and a latch on said cover engaging said stem.

10

3. A fomentation pad heater and wringer including a tank adapted to contain liquid; a cover hinged to said tank; means for heating said liquid; a squeeze plate within said tank to squeeze out the fomentation pad against said cover and having a rod extending through the cover; and means on said cover for raising and lowering said rod.

20

4. A fomentation pad heater and wringer including a tank adapted to contain liquid and having a cover; means for heating said liquid; a squeeze plate adapted to cooperate with said cover within said tank and having a rod at one end thereof extending upward through the cover; a removable tray on said squeeze plate adapted to receive the fomentation pad to be treated; a depresser adapted to engage the top of said pad; and means for moving said rod to raise or lower said squeeze plate with respect to said cover.
